UNITED STATES PATENT OFFICE.

OTTO E. SZEKELY, OF MOLINE, ILLINOIS.

WASHING MACHINE.

Application filed September 10, 1926. Serial No. 134,593.

Heretofore washing machines have been provided with integral or otherwise rigid impellers which move bodily in the tub as a solid element to wash the clothes, but because these impellers operate as one "dead" element they do not perform the washing operation with desirable speed and efficiency. Such an impeller moves up as one solid piece, a dead mass, in the tub, and while this type of impeller has been measurably successful I have found that it does not agitate the water and the clothes in the tub and does not create sufficient currents of water to cleanse the clothes speedily and efficiently.

The object of my invention is to provide a washing machine which performs the cleansing operation speedily and efficiently, and to this end it is also the object of my invention to provide a novel impeller which will whip the clothes in the water and create many conflicting currents in the water and drive the water through the clothes.

A further object of the invention is to provide a "live" impeller having a plurality of movable parts which will slap and whip the clothes back and forth in the tub and make the water pass back and forth through the clothes to thoroughly and speedily cleanse the clothes.

The invention has other objects in view incidental to the primary objects above recited and which will appear hereafter in the detail description of the invention, reference being had to the accompanying drawings illustrating selected embodiments of the invention, and referring to which:

Fig. 1 is a sectional elevation showing my invention embodied in one form in a washing machine tub.

Fig. 2 is a perspective view of the impeller shown in Fig. 1.

Fig. 3 is a top plan view of Fig. 1 with the cover parts removed.

Fig. 4 is a detail sectional view and Fig. 5 is a detail plan view showing another means for operating the impeller vanes.

Referring to the drawings 6 represents a pressed steel tub having a cover 7 removably supported on a cover rim 8. The tub has a central opening 9 in its bottom and a tubular support 10 projects through said opening into the tub and is provided with a base 11 which is fastened to the bottom of the tub by any suitable means. Vanes 12 are independently pivoted to the support, at the top and at the bottom thereof, and are arranged

at spaced intervals about the support and oscillate thereon. The bottom pivot for each vane comprises a stud 13 threaded in a boss 14 on the base 11 and projecting up into an opening 15 in the bottom of the vane close to the inner edge thereof. The top pivot comprises a stud 16 pressed and pinned into the upper end of the vane and projecting through an opening 17 in a head 18 on the upper end of the support 10. I provide the opening 15 and the opening 17 with bearings 15' and 17' made of bakelite or other suitable material. A sector gear 19 is rigidly mounted on the upper end of each of the studs 16 and meshes with a pinion 20 rigid on the drive shaft 21 which is mounted in bearings 22 in the tubular support 10. A cap 23 is bolted to the head 18 over the gears 19 and pinion 20.

The drive shaft 21 is oscillated to move the vanes back and forth in suitable arcs, by driving means suitable for the purpose and which may be varied more or less for different installations and to meet different conditions. In the drawings I have shown a simple drive comprising a crank 23 pinned on the lower end of the shaft 21, a crank pin 24 on the crank engaged with one end of the rod 25 which is engaged at its other end by means of a crank pin 26 with a crank 27 which is operated by a motor 28 through any suitable reduction means which may be desirable. There are many other mechanical drives, including the rack and pinion, which may be employed with my invention, but they are well known to those skilled in the art and since I do not claim them specifically I do not consider it necessary to show or describe more than one which I have selected because of its simplicity.

In Fig. 5 I have shown other means for imparting movement from the drive shaft to the vanes. This means is of a lever type comprising lever arms 29 rigidly mounted on the upper ends of the studs 16 and projecting into recesses 30 in the pinion 31 mounted on the drive shaft 21. It will readily be seen that oscillation of the drive shaft will produce an oscillating movement of the pinion 31 which will in turn actuate the lever arms 29 and move the vanes 12 back and forth just as they are moved back and forth through the gears in the construction of Figs. 1-3, as indicated in broken lines in Fig. 3.

My invention provides in a simple manner for causing the vanes to move in arcs described from the tubular center support within the tub, and all the vanes are moved 5 conjointly through suitable drive means. I have indicated two different means for oscillating the vanes but I do not limit the invention thereto because I believe that other oscillating means may be substituted which 10 will produce the desired oscillating movement of the vanes and thereby provide a "live" impeller for the machine.

When the machine is in operation the impeller vanes oscillate back and forth in their 15 predetermined arcs, and impart a more or less violent agitation to the clothes and the water in the tub, and create strong currents of water in the tub. But the action of the live impeller is especially important in driving 20 the water through the clothes which is so highly desirable for the washing operation, and this type of live impeller is so far superior to the dead impellers heretofore commonly used that the washing operation 25 is performed more speedily and with better cleansing efficiency. The superiority of my invention is due, as I now understand it, to the use of a live impeller instead of a dead impeller, and by this I mean an impeller 30 having movable vanes as distinguished from an impeller having rigid vanes.

The crank 25 and the connections with the shaft 21 are such that the vanes are given a variable speed as they rotate, the 35 vanes being positively actuated simultaneously and conjointly in varying arcs upon and about the shaft 21.

My invention consists broadly in the concept of a live impeller centrally disposed 40 within a washing machine tub and equipped with a plurality of radially projecting vertical vanes which are caused to swing in arcs described from the center support of the impeller. Changes may be made in the 45 construction and arrangement of parts and in the drive means, without departing from the spirit or sacrificing the advantages of my invention, and I reserve the right to make all such changes as fairly fall within 50 the scope of the following claims.

I claim:

1. A washing machine comprising a tub, and an impeller arranged within the tub and comprising a vertical support with radially 55 disposed parts at the top and at the bottom thereof spaced apart around the support, a plurality of vanes pivotally mounted in said radially disposed parts and projecting outwardly from the support, and means for 60 positively swinging said vanes separately in alternately varying arcs described from their pivots.

2. A washing machine comprising a tub, and an impeller arranged within the tub and 65 comprising a vertical support, a plurality of

vanes disposed radially within the tub about said support, pivot devices at the top and at the bottom of said vanes engaging said support to permit the vanes to swing in separate arcs, and means for positively swinging 70 the vanes and giving them a simultaneous and conjoint variable movement to and from said support as the vanes are oscillated.

3. A washing machine comprising a tub, and an impeller arranged within the tub and 75 comprising a tubular support, a plurality of vanes pivotally mounted radially about said support, a drive shaft in the tubular support, means operated by said drive shaft for swinging said vanes in separate arcs, and 80 means for oscillating said shaft.

4. A washing machine comprising a tub having an opening in the bottom thereof, and an impeller arranged within the tub and comprising a vertical tubular support 85 and a base secured to the margin of the tub around said opening, a plurality of vanes pivoted to the support at the top and bottom and radially disposed about the support, a drive shaft in said support, means 90 for oscillating said drive shaft, sector gears on the upper pivots of the vanes, and a pinion on the drive shaft meshing with said sector gear for swinging the vanes in separate arcs. 95

5. A washing machine comprising a tub, a vertical support therein, independently mounted vanes, an actuating member on said support, and means operatively connected with said actuating member to positively 100 actuate said vanes simultaneously and conjointly in varying arcs about said support.

6. A washing machine comprising a tub, a movable member mounted therein, impeller vanes independently mounted, and interengaging connections between said movable member and the mountings of the vanes, constructed to positively give to said 105 vanes a variable movement to and from the said support as the vanes are oscillated. 11

7. A washing machine comprising a tub, a movable member mounted therein, impeller vanes independently mounted, interengaging connections between said movable member and the mountings of the vanes, constructed to give to said vanes a positive variable movement to and from the said support as the vanes are oscillated, and means for alternately varying the speed of rotation of the vanes. 11

8. A washing machine comprising a tub, a vertical support therein, independently mounted vanes, an actuating member on said support, and oscillatory gear means operatively connecting said support and vanes for positively actuating said vanes simultaneously and conjointly and giving them alternate movement in varying arcs. 12

9. A washing machine comprising a tub, a vertical support therein, independently 13

mounted vanes, an actuating member on said support, said tub being multi-sided, and oscillatorily mounted means between said support and vanes for positively giving the vanes alternately opposite oscillation in varying arcs about said support.

10. A washing machine comprising a tub and an impeller centrally supported within

the tub and comprising a plurality of independently oscillatory radially extending vanes, the lower edges of the vanes being spaced apart and arranged in clearing relation to the bottom of the tub, said vanes being mounted for positive swinging movement independently of each other.

OTTO E. SZEKELY.
